(57) **CLAIM**

The ornamental design for a cloth clip for an embroidery machine, as shown and described.

DESCRIPTION

FIG. 1 is a front, left perspective view of the cloth clip for an embroidery machine, showing my ornamental design;

FIG. 2 is a front elevation view thereof;

FIG. 3 is a right elevation view; thereof, the left side being identical;

FIG. 4 is a rear elevation view thereof;

FIG. 5 is a top plan view thereof; and,

FIG. 6 is a bottom plan view thereof.

1 Claim, 2 Drawing Sheets

FIG. 5

FIG. 6
